EARRING

Herman Bogoff, Chicago, Ill.

Application August 3, 1949, Serial No. 4,277

Term of patent 3½ years

(Cl. D45—9)

To all whom it may concern:

Be it known that I, Herman Bogoff, a citizen of the United States, residing at Chicago, in the county of Cook and State of Illinois, have invented a new, original, and ornamental Design for an Earring, of which the following is a specification, reference being had to the accompanying drawing, forming part thereof, wherein

Fig. 1 is an elevational view of one side of an earring, showing my new design;

Fig. 2 is a front elevational view thereof; and

Fig. 3 is an elevational view of the earring side opposite that shown in Fig. 1.

I claim:

The ornamental design for an earring, as shown.

HERMAN BOGOFF.
